JUKEBOX

Walter Herbst, Evanston, Ill., assignor to NSM Apparatebau G.m.b.H. Kommanditgesellschaft, Bingen (Rhine), West Germany

Filed May 19, 1972, Ser. No. 255,315

Term of patent 14 years

Int. Cl. D14—01

U.S. Cl. D56—4 R

FIG.4

FIG.1

FIG. 2

FIG. 1 is a front elevational view of a jukebox, showing my new design;

FIG. 2 is a left side elevational view;

FIG. 3 is a right side elevational view; and

FIG. 4 is a top plan view thereof.

The rear side and the bottom are substantially unornamented.

I claim:

The ornamental design for a jukebox, as shown and described.
